UNITED STATES PATENT OFFICE.

CHARLES OWEN REED, OF CHICAGO, ILLINOIS.

GUSSET FOR WEARING-APPAREL.

SPECIFICATION forming part of Letters Patent No. 269,463, dated December 19, 1882.

Application filed July 8, 1882. (No model.)

To all whom it may concern:

Be it known that I, CHARLES OWEN REED, of Chicago, in the county of Cook and State of Illinois, have invented a new and Improved 5 Gusset for Wearing-Apparel, of which the following is a full, clear, and exact description.

The object of my invention is to provide a new and improved stay or gusset for wearing-apparel, which is stronger and more durable 10 than the gussets in use heretofore, which can be attached more rapidly, and is thus cheaper, and which presents a very neat appearance and finish.

The invention consists in a gusset formed of 15 a strip of material having its ends tapered, which gusset is preferably made in the shape of a lengthened and pointed ellipse.

The invention also consists in the method of attaching the gusset by placing the edge of the 20 gusset on the edge of the material, and sewing on the gusset at the same time while forming the hem and by the same stitches.

Reference is to be had to the accompanying drawings, forming part of this specification, in 25 which similar letters of reference indicate corresponding parts in all the figures.

Figure 1 is a representation of part of a shirt, showing the gusset partly attached to the side slit at the bottom of the shirt. Fig. 2 is a longitudinal view of the gusset. Fig. 3 is a longitudinal view of the same, showing it folded. Fig. 4 is a longitudinal view of a modification of the same. Fig. 5 is a view of the back-opening of a shirt provided with my improved gusset. Fig. 6 is a cross-sectional view of the same 35 on the line *x x*, Fig. 5. Fig. 7 is a back view of a shirt provided with a cut or slit, at the lower end of which the gusset is to be attached. Fig. 8 is a view of a sleeve provided with a 40 slit, at the inner end of which the gusset is to be attached.

The gusset or stay A is made in the shape of a strip with tapered ends, or a lengthened ellipse with the ends pointed, as shown in Fig. 2; or it is made in the shape of half of the pointed lengthened ellipse A', as shown in Fig. 4, the straight edge being hemmed; or it can be made from the selvage-edge of the cloth, which does not require to be folded or stitched, as it

can resist fraying. The gusset could be made 50 with the raw edge exposed; but this is not desirable, as it would fray out and soon give way. I prefer to use the gusset A, (shown in Figs. 2 and 3,) as it is stronger and can be made more easily. The gusset A is folded on 55 its longitudinal central line, so that it will have the shape of half of a lengthened pointed ellipse of double thickness. For instance, if the gusset is to be attached to the upper parts of a slit, B, formed at the lower end of the 60 side of a shirt, where the front and back pieces are united, the edge of the back C is hemmed to within a short distance from the upper end of the slit B, and then the gusset is placed on the inner side of the back C in such a manner 65 that the rounded edge of the gusset rests on the edge of the slit which is folded over the edge of the gusset, and the hem is completed up to the upper end of the slit, whereby the gusset will be attached by the same stitches 70 that secure the hem. Then the other half of the gusset is placed on the edge of the front D at the slit, and the edge of this front is hemmed. The gusset A' is attached in a like manner. In a like manner the gusset can be 75 attached to the slit E in the back of a shirt, or to a slit, F, in a sleeve, G, to drawers, petticoats, dresses, undershirts, night-shirts, or to any other article of wearing-apparel. If the end of the slit is formed as shown in Fig. 5, 80 the gusset is carried around it. If desired, the ends of the gusset may be blunted or cut off.

The gusset can be made of the same material as the article to which it is to be attached, or of different material. For instance, linen, 85 cloth, silk—plain or oiled—leather, or chamois-skin may be used.

This gusset can easily be cut from the waste pieces or scraps of the material.

This gusset is very strong and durable, and 90 can be attached very rapidly, as it is attached at the same time that the hem is made and by the same stitches. It is very neat, and has a perfect finish, and is smooth, so that it cannot catch and rip off when the shirt is laundered. 95

I am aware an endless gusset has been employed at an opening in a shirt, and I therefore do not claim such, broadly.

Having thus described my invention, what I claim as new, and desire to secure by Letters Patent, is—

The combination, with a shirt or other garment provided with a slit, of the lengthened and pointed ellipse-shaped gusset adapted to be folded on its longitudinal axis, and to have its round edges only stitched to the edges of

the slit of the garment, between the body of the same and the hem, substantially as herein shown and described.

CHARLES OWEN REED.
